UNITED STATES PATENT OFFICE.

BERNHARD WILENTSHIK, OF NEW YORK, N. Y.

DESIGN FOR A BELT.

SPECIFICATION forming part of Design No. 35,571, dated January 7, 1902.

Application filed December 14, 1901. Serial No. 85,994. Term of patent 7 years.

To all whom it may concern:

Be it known that I, BERNHARD WILENTSHIK, a citizen of the United States, and a resident of the city of New York, borough of Manhattan, in the county and State of New York, have invented and produced a new and original Design for a Belt, of which the following is a full, clear, and exact description.

Reference is to be had to the accompanying drawings, forming a part of this specification, in which similar characters of reference indicate corresponding parts in all the figures.

Figure 1 is a face view of a belt, showing my design. Fig. 2 is a rear face view of the same, and Fig. 3 is a transverse section of the same on the line 3 3 in Fig. 1.

The design in its entirety consists of a front band of single pieces resembling overlapping leaves A, extending in opposite directions from an ornamental central piece B and ter-

minating in ornamental connecting-pieces C, the overlapping points of the leaves appearing with heads D and the leaves appearing on a back band E, extending from one end piece C to the other end piece.

The leading feature of the design consists of a band of single pieces resembling leaves.

Having thus described my invention, I claim as new and desire to secure by Letters Patent—

The design for a belt, as herein shown and described.

In testimony whereof I have signed my name to this specification in the presence of two subscribing witnesses.

BERNHARD WILENTSHIK.
